UNITED STATES PATENT OFFICE.

CHARLES G. OBERLEY AND ROBERT GRIGNON, OF MUNISING, MICHIGAN.

FRICTION CLUTCH.

Application filed April 20, 1920. Serial No. 375,321.

To all whom it may concern:

Be it known that we, CHARLES G. OBERLEY and ROBERT GRIGNON, citizens of the United States, residing at Munising, in the county of Alger and State of Michigan, have invented new and useful Improvements in Friction Clutches, of which the following is a specification.

This invention relates to improvements in friction clutches of that type wherein two concentric drum-like parts and intermediate clutch band means are employed, the function of the clutch band means being to connect the companion parts whereby one is driven from the other, or to disconnect the companion parts whereby the driving part runs free.

The principal objects of the invention are to provide a simply constructed clutch which shall have great efficiency in the operation of the band-connecting means, which shall be adaptable without the necessity of adjustment or re-arrangement of any parts for driving rotation in either direction, and wherein the elements are specially arranged to avoid side pull on the companion drum members which would tend to interfere with their alinement; to provide for ready adjustment of the tension of the bands; and to provide for simplicity and facility of operation as regards the connection or disconnection of the companion drum-like parts.

An embodiment of the invention is illustrated in the accompanying drawings, where-

in:

Figure 1 is an elevation.

Figure 2 is an elevation from which the inner drum-like part has been omitted in order to show the internally arranged elements.

Figure 3 is a view showing the outer drum in section on line 3—3, Figure 1, and the inner drum in elevation.

Figure 4 is a vertical longitudinal section on the line 4—4, Figure 2, showing the drum-like parts as operatively connected.

Figure 5 is a similar sectional view on line 5—5, Figure 1, and at right angles to the sectional line of Figure 4.

Figure 6 is a perspective view of one of the operating heads.

Figure 7 is a perspective view of one of the operating levers.

Similar characters of reference designate

corresponding parts throughout the several views.

In the example disclosed, power is to be transferred from one shaft to another, the two shafts being shown at 1 and 2 in alinement relation. The companion drum-like parts above referred to are shown at 3 and 4, the part 3 being keyed or otherwise fast on the shaft 1 and enclosing the part 4 which is fast on the shaft 2.

Two clutch bands 5 and 6 are provided, these being arranged in lateral adjacency and each having an extent of nearly a circle, the terminals of one band being located in substantially diametrically opposite relation to the terminals of the other band. The terminals of the band 5 are connected to operating levers 7 and 7^a and the terminals of the band 6 are connected to operating levers 8 and 8^a. The part 3 includes a flat web 9 to which the levers 7 and 8 are directly pivoted, as at 10. The respective companion levers 7^a and 8^a are carried by an adjusting ring 11 and are pivoted, as at 12, at diametrically opposite points of said ring. The ring 11 is mounted upon a concentric annular shoulder 9^a which projects beyond the rear side of the web 9 and the pivots 12 project through suitable apertures 14 in said web. The ring 11 is preferably provided with circumferentially curved slots 15 located at diametrically opposite points through which project the shanks of suitable fastenings 16 which are secured in the web 9, these fastenings holding the ring against both endwise and circumferential displacement. The ring 11 is adjusted circumferentially by a screw 17 which is threaded in a lug 18 carried by said ring and, projecting at a suitable angle to the radius, exerts its thrust against a lug 19 provided on the part 3 at the outer side of the web 9. The levers 7 and 7^a and 8 and 8^a are pivoted somewhat near their outer extremities where they are provided with angular arms 20 which serve for their connection to the ends of the bands 5 and 6 in the relation explained. The body portions of said levers are arranged between the part 4 and the web 9 and their inner ends, which are free, bear against laterally and radially movable operating heads 21,

each of which is common to adjacent levers of the respective pairs, that is to say, one operating head 21 is common to the levers

7 and 8^a and the other is common to the levers 7^a and 8. The operating heads 21 are arranged in diametrically opposite relation immediately adjacent the web 9 and under 5 the levers with which they cooperate. Each operating head has a forwardly directed V-shaped projection whose convex side is related symmetrically to the adjacent lever terminals and provides two angularly disposed 10 surfaces 23 for cooperation with said lever terminals. The V-shaped projection 22 is raised merely to provide walls for the recesses within which the ends of the pairs of levers 7 and 8^a and 7^a and 8 are retained. 15 The levers 7, 7^a, 8 and 8^a are spaced from the web 9 from their outer ends a distance equal to the thickness of the operating heads 21 upon which they lie. At their pivotal bosses 10 and 12 the said levers are provided 20 with spacing projections 12^a, Figure 7, of the same thickness as the operating heads and they are provided with third arms having projections 13 provided with smooth anti-friction surfaces which ride upon similar 25 anti-friction surfaces 13^a and 13^{a'} on the web 9, the height of the projections 13 and the anti-friction surfaces being such that each of the levers is held at a uniform distance from the web 9 by its three points of support. 30 The anti-friction surfaces 13^a and 13^{a'} act as smooth sliding surfaces for the third arms of the levers and are elongated to accommodate the travel of the projections 13 when said levers are operated. The anti-friction 35 surfaces 13^{a'} are longer than the anti-friction surfaces 13^a to allow for the movement of the levers 7^a and 8^a when the adjusting ring is turned. 40 The inner terminal portions of the levers are normally moved inward by springs 24, preferably retractile spiral springs, which connect the levers of the respective pairs and in this way the operating heads 21 are held 45 against the longitudinally movable pins 25 by which they are operated, said pins working symmetrically against the concave surface 26 of the projection 22 and having cam terminals 27 which are effective to provide 50 for the lateral radial movement, simultaneously in opposite directions, of the heads 21. The pins 25 are parallel to the alining shaft and are provided with shanks 27^a which project slidably through bearings 28 carried by 55 the web 9. At their outer ends said pins are connected to an operating yoke 29 by which they are moved in either direction. When said pins are moved inward, as shown in Figures 1 to 4, they effect the lateral movement of the heads 21 in the outward direction, said heads, in turn, moving the levers to apply both of the bands upon the periphery of the part 4 with the requisite degree of force. Disengagement of the bands is 60 effected by moving the pins 25 outward as 65

shown in Figure 5, the springs 24 at such time moving the levers whereby the bands are certainly disengaged from the periphery of the part 4 and the inner terminals of the levers, acting on the heads 21, cause said 70 heads to move inward as permitted by the cam outline of the pins 25. It will, of course, be apparent that the operating heads are held in operative position without the aid of positive fastenings, said heads being confined by the parts with which they cooperate against displacement relatively to said parts, except in the manner and direction described. 75

If desired, the peripheral portion of the part 3 may be provided with inwardly extending radially disposed projections 30 which prevent the clutch bands, when disengaged from the peripheral portion of the part 4, from rubbing against the inner circumferential face of the part 3. 85

Having fully described our invention, we claim:—

1. In a friction clutch, a pair of drum-like members, a clutch band for engagement with one of said members, a pair of levers pivotally supported on the other member, each connected at its outer end to one end of said clutch band, the pivotal support of one lever being fixed and that of the other being adjustable, radially movable operating heads embracing the inner ends of said levers for tightening the band. 90

2. In a friction clutch, a pair of drum-like members, a clutch band for engagement with one of said members, a pair of levers pivotally supported on the other member, each connected at its outer end to one end of said clutch band, the pivotal support of one lever being fixed and that of the other being adjustable, radially movable operating heads engaging the inner ends of said levers, and cams movable axially of said clutch for actuating said operating heads. 100

3. In a friction clutch, a pair of drum-like members, a clutch band for engagement with one of said members, a pair of levers pivotally supported on the other member, each connected at its outer end to one end of said clutch band, and freely mounted radially movable operating heads engaging the inner ends of said levers and cooperating smooth contacting surfaces on said levers and the member to which said levers are secured. 110

4. In a friction clutch, a pair of drum-like parts, one of which has a flat web, a pair of clutch bands operative to connect said parts and each having their terminals in adjacency, the terminals of one band being located in opposite relation to the terminals of the other band, oppositely located pairs of levers whose outer ends are connected to the respective terminals of the bands, the levers of one pair having their inner ends adjacent 125

the inner ends of the respective levers of the other pair, radially movable operating heads, each bearing against the adjacent inner ends of said levers, and means for moving said 5 operating heads.

5. In a friction clutch, a pair of drum-like parts, one of which has a flat web, an adjusting ring mounted concentric to said web, a pair of clutch bands operative to connect 10 said parts and each having their terminals in adjacency, the terminals of one band being located in opposite relation to the terminals of the other band, oppositely located pairs of levers whose outer ends are connected to the 15 respective terminals of the bands, oppositely located levers of the pairs being pivoted to

said web and to said ring, respectively, the levers of one pair having their inner ends adjacent the inner ends of the respective levers of the other pair, radially movable 20 operating heads, each bearing against the adjacent inner ends of said levers, and means for moving said operating heads.

In testimony whereof we have hereunto set our hands in presence of two subscribing 25 witnesses.

CHARLES G. OBERLEY.
ROBERT GRIGNON.
